UNITED STATES PATENT OFFICE.

HARRY S. SMITH, OF NEEDHAM HEIGHTS, MASSACHUSETTS, ASSIGNOR, BY MESNE ASSIGNMENTS, TO THE GAMEWELL COMPANY, OF NEWTON, MASSACHUSETTS, A CORPORATION OF MASSACHUSETTS.

SIGNAL-DEVICE-OPERATING MECHANISM.

Application filed December 19, 1919. Serial No. 346,023.

To all whom it may concern:

Be it known that I, HARRY S. SMITH, a citizen of the United States, residing at Needham Heights, in the county of Norfolk and State of Massachusetts, have invented an Improvement in Signal-Device-Operating Mechanism, of which the following is a specification.

My present invention relates to a signal device adapted to sound code signals, as for fire alarms, and has more specific reference to a whistle and its controlling means employed for this purpose.

It is highly desirable that a whistle employed for the purpose above set forth should sound a signal, the individual blasts of which are of a uniform and invariable length to prevent the misinterpretation of signals. The usual operating means for the signal device has been a "whistle blowing machine" which is an electro-mechanically controlled, weight driven device occupying considerable space and necessitating continual attention. This device, as usually installed, is remote from the whistle valve and is connected therewith by a cable passing over pulleys. Control devices have been designed which are closely associated with the whistle valve but these have the fault of being complicated and getting out of adjustment, and failing to sound uniform signal blasts.

An object of my invention is the provision of a signal device operating mechanism arranged to sound uniform signal blasts.

A further object is to assemble the whistle valve and its controlling and operating mechanism as a single unit.

A further object of my invention is to provide means for varying the period of the blasts.

I employ an electro-magnetically controlled mechanism for the operating mechanism and a yet further object of my invention is to provide power actuated means for positively resetting the electro-magnetically controlled mechanism.

Another object of my invention is the arrangement of the mechanism by which a non-interference of signals is obtained whereby, after the initial signal impulse to operate the mechanism, further impulses are without effect in mutilating the signal blast.

A further object is to provide my control-

ling device as an attachment for existing 55 whistle valves.

Fig. 1 is a sectional view of signal device operating mechanism embodying my invention.

Fig. 2 is a front end view detail of my 60 controlling apparatus removed from the whistle valve.

Fig. 3 is a sectional detail along line 3—3 of Fig. 2 illustrating more particularly the power-actuated resetting means for 65 the controlling mechanism.

Fig. 4 is a sectional detail along line 4—4 of Fig. 2 illustrating the positively operated exhaust valve and its mechanism.

Fig. 5 is a rear end view of the controlling 70 mechanism.

As here shown the whistle valve includes the casing 10 having the outlet passage 11 into which is connected the pipe 12 extended to the whistle, not shown, and the inlet passage 13 into which is connected the pipe 14 extended to a pressure source, as a steam boiler, or a compressed air reservoir, not shown. A valve 15 controls the flow of fluid through the casing and has its stem fixed to the piston 16. Said piston is of substantially greater diameter than said valve and operates within the cylinder 17. The end of said cylinder is closed by the cap 18. Steam or air is adapted to be admitted behind said piston to cause it to open said valve to sound the blast and, after the proper length of blast has been sounded, the pressure is reduced and the pressure on said valve causes it to be seated, thereby to complete the blast.

For the purpose of governing the opening and closing of the main valve 15, an auxiliary or pilot valve 19 is employed which is disposed in the pressure passage 13 and, by reason of spring 19^a, normally maintains closed the port 20 from which extends the passage 21 in communication with the cylinder 17. The opening of said pilot valve admits high pressure fluid into said cylinder 17 to cause the main valve to open and, upon the closing of said pilot valve, the pressure drops due to the escape of fluid through leak passages, not shown, and the main valve consequently closes.

The pilot valve 19 is controlled by the normally balanced piston 22 secured to the valve stem 19^b and operates within a cylinder 23

formed in the valve casing which is in open communication with the pressure chamber 13 at one end. Said casing, about said cylinder, is exteriorly threaded and has received thereon the control member 25 having the end wall or face 26 forming the head for said cylinder. Said piston 22 is a relatively loose fit within its cylinder to admit of a restricted fluid leakage past it, into the space between it and the end wall 26. When the pressure on both sides of the piston is the same, the piston is balanced and the spring 19^a is permitted to close said pilot valve.

15 The governing of the whistle valve and the timing of its period of opening is effected through the governing of the pressure conditions between the piston 22 and the end wall 26.

20 A recess 28 is formed in said end wall 26 and the head of a poppet valve 29 is received therein and normally closes the passage communicating with the chamber 30 in said member 25. Said chamber 30 is cylindrical in bore and a sleeve valve 31 is slidably received therein. Said sleeve valve has its end portion extended beyond said chamber in communication with the atmosphere and for engagement with operating mechanism hereinafter to be described. An exhaust port 32 extends from said chamber 30 to the atmosphere and said sleeve valve is adapted to control the flow of fluid therethrough.

Said poppet valve is formed with a shoulder portion 33 under its head which is adapted to engage the end of the sleeve valve during certain parts of the operation of the mechanism, and a reduced stem 34 slidable within said sleeve valve and extended there-through to the atmosphere for engagement with operating mechanism.

35 A passage 35 extends from said chamber 30 to a recessed portion 36, and said recess is interiorly threaded to receive the end of a 40 nipple 37. A pipe 38 is received in said nipple and its end is closed by the cap 39. The volume of said pipe, and the passages extended therebetween to the poppet valve 29 govern the duration of the signal blast. 45 By varying this volume, as by substituting pipes of differing lengths or volumes, the period of the blast may be regulated and the device may be timed to any signal circuit.

Said pipe acts as a timing chamber and, in 50 effect, measures the period of the blast, by measuring a predetermined volume of fluid. The fluid leaking past the piston is received in said chamber, which has a definite capacity and a definite period of time is required to fill it; and when the chamber is 55 full, as measured by the equalization of pressure on both sides of the piston, the pilot valve is caused to close, thereby to terminate the signal blast.

60 65 The result of opening the poppet valve 29

is to permit a flow of fluid from the cylinder 23 into the chamber 30 and through the exhaust port 32 thereby to unbalance the piston 22 and cause the pilot valve and thereafter the main valve to open. It is essential to build up a pressure in the timing chamber and means are provided for causing the sleeve valve to close the exhaust port subsequent to the opening of the poppet valve; which means are illustrated more particularly in Fig. 4.

70 Said member 25 is formed with a lug or ear 40 rising therefrom and a lever 41 is pivoted thereto. Said lever has one arm thereof extended on one side of its pivoted support to engage the protruding end of said sleeve valve 31, and the other arm thereof extends to the other side of its pivoted support and is engaged by the plunger 42, one end of which extends through said member 25 from the spring recess 43 therein and the other end of which extends through a plug 44 threaded in said recess 43 into the cylinder 23. A spring 45 normally tends to hold said plunger away from said lever 41 and maintains it within said cylinder.

75 As said pilot valve is caused to open, its stem 19^b, or the piston 22, engages the end of said plunger 42 and, through the rocking of said lever 41, moves the sleeve valve 31 within its chamber to close the exhaust port and permit the building up of pressure in the timing chamber.

80 The control mechanism for the poppet valve includes the electro-magnet 46 supported on the bracket 46^a extended from the circular base plate 47 integral with or fixed to said member 25.

85 An armature 48 is pivoted to a lug 49 extended from said base plate and has the double pawls 50. Said armature controls the poppet valve operating mechanism including the toggle comprising member 51 and 52. Toggle member 51 is pivoted at 53 to the bracket 46 and has an arm 54 extended toward said armature bearing the detent 55 engageable with and releasable from said pawls.

90 95 The toggle member 52 is pivoted to the other member at 56 and also to the arm 57 mounted on the shaft 58 journaled between adjustable screw bearings 59 secured in lugs 60 in said base plate 47.

100 Said arm 57 is integral with or fixed to a hub 61 fixed to said shaft and has the hammer 62 at its end which is arranged to impact with the end of the poppet valve 29 to force it open upon the release of the toggle members. Said toggle members are normally slightly undershot in their locked condition and a strong spring 63 is connected between said arm 57 and said bracket 46 to positively break the toggle upon its release by the armature of the electromagnet and cause said hammer 62 to impact with con-

siderable force against the stem of the poppet valve.

Power actuated means are provided to positively reset the poppet valve control mechanism which is also arranged to hold said mechanism in reset condition during the sounding of a signal blast thereby to prevent possible mutilation of signals. Said means include the piston 65 operating in the cylinder 66 formed in said member 25. A passage 67 extends between the recess 36 comprising a component of the timing chamber and said cylinder 66 and admits steam or other fluid pressure therein to act upon said piston. A cap 68 closes the end of the cylinder. Said piston 66 has a stem 69 extended through said member 25 and the base plate 47 and is adapted to be engaged by, or be in proximity to the arm 54 of the toggle mechanism in its released or operated position.

A spring 70 encircling said stem 69 normally serves to retract said stem and piston within said cylinder 66.

Upon the occurrence of a signal impulse and the consequent tripping of the poppet valve control mechanism, a pressure is built up within the timing chamber. This pressure acts upon said piston 65 to force it outward into engagement with said arm 54 to restore the mechanism, and to lock it against further operation for so long as pressure endures in said timing chamber and consequently for the duration of a blast.

A cover 75 is secured to said base plate 47 by suitable means and encloses the entire control mechanism.

The operation of the device is as follows:

Assuming the normal condition of the apparatus to be as in Fig. 1, upon the occurrence of a signal impulse the toggle members are broken and the poppet valve is forcibly opened and the fluid under pressure in cylinder 23 escapes through the exhaust port 32. The piston 22 is consequently unbalanced and the pilot valve 19 is opened causing the main valve 15 to open and the initiation of the blast.

As the pilot valve opens, its stem, or its piston 22, engages the end of plunger 42 and moves it outwardly thereby causing the sleeve valve 31 to move to cover the exhaust port 32 and take control of and hold open the poppet valve during and also after the building up of pressure in the timing chamber. Due to the closing of the exhaust port and the opening of the poppet valve pressure begins to be built up in the timing chamber from the main valve casing because of the designed clearance past the piston 22. At some point in the process of pressure building, the resetting piston 65 is forced outwardly to engage the arm 54 of the poppet valve mechanism and reset and lock it in reset position against a subsequent

release due to subsequent signal impulses during the continuance of the signal blast.

After a certain interval of time, during which the blast is being sounded, which time is determined by the volume of the timing chamber and the rate of leakage past the piston 22, pressure on both sides of said piston becomes equal and the piston is consequently balanced. Spring 19^a now operates to force the pilot valve closed and the main valve is also closed and the blast is terminated. Plunger 42 is no longer held in its outwardly moved position by the pilot valve and is forced inwardly against the pressure within said cylinder 23 by its spring 45. The poppet valve and the sleeve valve are now no longer held in an operated position against the pressure within the timing chamber and the poppet valve is forced against its seat by said pressure and the sleeve valve is simultaneously moved outward thereby permitting the poppet valve to close and subsequently opening the port 32 to exhaust the timing chamber.

The device is now in condition to sound another signal blast.

The device is adapted as an attachment to existing whistle valves and may be applied thereto by removing a cap, not shown, secured to the threaded portion of the cylinder 23 of said valve casing 10, and substituting therefor the member 25 with its associated mechanism.

It is obvious that many modified forms of the apparatus herein described may be made without departing from the spirit of my invention.

I claim:

1. Signal device operating mechanism including, in combination with a piston and a cylinder in which it operates having provision for the restricted flow of fluid from one to the other end thereof, a timing chamber, and means controllable by said piston to govern fluid communication between said cylinder and timing chamber.

2. Signal device operating mechanism including, in combination with a piston and a cylinder in which it operates having provision for the restricted flow of fluid from one to the other end thereof, a timing chamber, and means controllable by said piston to govern fluid communication between said cylinder, timing chamber and the atmosphere.

3. Signal device operating mechanism including, in combination with a piston and a cylinder in which it operates having provision for the restricted flow of fluid from one to the other end thereof, a timing chamber, and mechanism governing the fluid condition of said cylinder and timing chamber, said mechanism comprising means for governing fluid communication with the atmosphere and means operable independently of

said first named means for governing fluid communication between said cylinder and timing chamber.

4. Signal device operating mechanism including, in combination with a piston and a cylinder in which it operates having provision for the restricted flow of fluid from one to the other end thereof, a timing chamber arranged for fluid communication with 10 said cylinder and with the atmosphere, and independently operable valves governing communication with said cylinder and the atmosphere.

5. Signal device operating mechanism including a valve, a fluid measuring device adapted for connection with a source of fluid pressure, means to admit fluid into said device, and means operable incident to the opening of said valve to permit closure 20 thereof only after the passage of a predetermined amount of fluid into said measuring device.

6. Signal device operating mechanism including a valve, a fluid measuring device adapted for connection with a source of fluid pressure, means to admit fluid into said device, means to operate said valve upon the passage into said device of a predetermined amount of fluid, and fluid operable means governed alternately by the positioning of said valve and by the fluid conditions of said device for controlling the escape of the measured fluid.

7. Signal device operating mechanism including a valve, a chamber adapted for connection with a source of fluid pressure, means operable in response to changes in and for governing the fluid conditions of said chamber, and means governed by fluid conditions within said chamber to operate said valve.

8. Signal device operating mechanism including a valve, a chamber adapted for connection with a source of fluid pressure, means responsive to movement of said valve for governing the flow of fluid thereinto, means governing the flow of fluid therefrom, and means governed by fluid conditions within said chamber to operate said valve.

50 9. Signal device operating mechanism including a valve, a chamber adapted for connection with a source of fluid pressure, means responsive to movement of said valve for governing the flow of fluid therein, and means governed by fluid conditions within said chamber to operate said valve.

60 10. Signal device operating mechanism including a valve, a chamber adapted for connection with a source of fluid pressure, means to restrict the flow of fluid therein, means responsive to movement of said valve providing for escape of fluid therefrom, and means governed by fluid conditions within said chamber to operate said valve.

65 11. Signal device operating mechanism in-

cluding a normally balanced piston, a cylinder in which it operates arranged for restricted fluid leakage between its ends, a timing chamber having communication with said cylinder and with the atmosphere, a 70 valve controlling communication between said chamber and cylinder, electrically controlled operating means therefor, a valve controlling communication between said chamber and the atmosphere, and means 75 governed by said piston for operating it.

12. Signal device operating mechanism including a normally balanced piston, a cylinder in which it operates arranged for restricted fluid leakage between its ends, a 80 timing chamber arranged for fluid communication with said cylinder, a valve governing said fluid communication, said timing chamber also arranged for atmospheric communication, a second valve operable independently of said first valve and governing such communication, and operating mechanism arranged to permit flow of fluid from said cylinder to said chamber and to the atmosphere thereby to unbalance the 90 piston for its operation, said second valve thereupon adapted to close to cause a pressure to be built up within said chamber and cylinder thereby to restore the balance on said piston, and said first valve adapted to 95 thereafter close to isolate said chamber and cylinder, and said second valve adapted to thereupon open to permit escape of fluid from said chamber.

13. The method of operating a signal device operating mechanism having a normally balanced piston which consists in initially unbalancing the piston to cause its operation, connecting the cylinder of the device to a closed chamber to cause pressure to be 105 built up in said chamber and cylinder, whereby balance is restored and said piston operated, isolating said chamber and cylinder upon attainment of predetermined pressure in said chamber and causing the 110 discharge of fluid from said chamber only after attainment of such chamber pressure.

14. The method of operating a signal device operating mechanism having a fluid pressure actuated component, which consists 115 in causing a restricted flow of fluid from the mechanism, measuring said fluid and causing the actuation of said component to permit escape of measured fluid when a predetermined measured quantity has passed. 120

15. Signal device operating mechanism including a normally balanced piston, a cylinder in which it operates adapted for connection with a source of fluid pressure, means to unbalance it including a valve, 125 means to restore its balance including a timing chamber into which said cylinder is adapted to discharge and an escape valve controlled by said piston.

16. Signal device operating mechanism in- 130

- cluding a normally balanced piston, a cylinder in which it operates adapted for connection with a source of fluid pressure, means including a valve for causing the unbalancing and subsequent rebalancing of the piston, normally locked valve operating mechanism, means to release it to operate the valve and fluid actuated restoring means for said operating mechanism.
17. Signal device operating mechanism including a normally balanced piston, a cylinder in which it operates adapted for connection with a source of fluid pressure, means including a valve for causing the unbalancing and subsequent rebalancing of the piston, normally locked valve operating mechanism, means to release it to operate the valve and fluid actuated restoring means for said operating mechanism operating to hold said mechanism in restored position during the rebalancing of said piston.
18. Signal device operating mechanism including a normally balanced piston, a cylinder in which it operates adapted for connection with a source of fluid pressure, a timing chamber arranged for fluid communication with said cylinder, a valve to govern the flow of fluid therebetween, normally locked valve operating mechanism, means to release it to operate the valve, and mechanism restoring means including a piston associated with said timing chamber actuated by pressure conditions therein.
19. Signal device operating mechanism including a valve, adapted to be opened to sound a signal, operating means therefor including normally locked mechanism releasable to cause the opening of the valve, and restoring means for said mechanism arranged to hold said mechanism in restored position during the period of opening of the valve.
20. Signal device operating mechanism including, in combination with a piston and a cylinder in which it operates having provision for the restricted flow of fluid from one to the other end thereof, a timing chamber arranged for fluid communication with said cylinder and with the atmosphere, independently operable valves, and means to operate them successively to govern communication with said cylinder and with the atmosphere.
21. Signal device operating mechanism including a valve, a fluid measuring device adapted for connection with a source of fluid pressure, signal initiating means operable to cause the opening of said valve, and means to prevent operation of said initiating means following the closing of said valve for a predetermined period measured by the flow of fluid from said device.
22. Signal device operating mechanism including a valve, a fluid measuring device adapted for connection with a source of fluid pressure, signal initiating means operable to cause the opening of said valve, and means to prevent the closing of said valve until it has remained open for a predetermined period measured by the flow of fluid in said device.
23. Signal device operating mechanism including a valve, a fluid measuring device adapted for connection with a source of fluid pressure, signal initiating means operable to cause the opening of said valve, and means to cause the closing of said valve after a predetermined period following the opening thereof, and so constructed and arranged that the duration of such period is measured by the flow of fluid in said device and is unaffected by said initiating means between the opening and closing of said valve.
24. Signal device operating mechanism including a valve, a fluid measuring device adapted for connection with a source of fluid pressure, signal initiating means operable to cause the opening of said valve, and means to render the control of said valve unaffected by said initiating means from the opening thereof until after the expiration of a predetermined period following the closing thereof.
25. Signal device operating mechanism including, in combination with a piston and a cylinder in which it operates having provision for the restricted flow of fluid from one to the other end thereof, a timing chamber, and means operable by said piston to govern fluid communication between said cylinder and an exhaust port.
26. Signal device operating mechanism including, in combination with a piston and a cylinder in which it operates having provision for the restricted flow of fluid from one to the other end thereof, a timing chamber, and means to govern communication between said cylinder and timing chamber operable to terminate such communication only in response to the flow of fluid therebetween.
27. Signal device operating mechanism including, in combination with a piston and a cylinder in which it operates having provision for the restricted flow of fluid from one to the other end thereof, a timing chamber, means jointly controlled by said piston and by fluid conditions within said chamber to govern fluid communication between said cylinder, timing chamber and the atmosphere.
28. Signal device operating mechanism including, in combination with a piston and a cylinder in which it operates having provision for the restricted flow of fluid from one to the other end thereof, a timing chamber, means to govern fluid communication between said cylinder and timing chamber, actuating mechanism operable to cause said means to establish communication between said cylinder and chamber, and a member

- operable by the fluid conditions within said chamber to prevent such operation of said means.
29. Signal device operating mechanism including, in combination with a piston and a cylinder in which it operates having provision for the restricted flow of fluid from one to the other end thereof, signal initiating mechanism, a timing chamber, means operable by said initiating mechanism to establish fluid communication between said cylinder and timing chamber, and means operable by said piston for maintaining said first means in such operated condition.
- 15 30. Signal device operating mechanism including, in combination with a piston and a cylinder in which it operates having provision for the restricted flow of fluid from one to the other end thereof, a timing chamber, means to govern fluid communication between said cylinder, said timing chamber and the atmosphere, signal initiating mechanism for operating said connecting means to connect said cylinder with said chamber, and fluid pressure operable means to govern the duration of the connection of said cylinder with said timing chamber and to govern the connection of said timing chamber with the atmosphere.
- 20 31. Signal device operating mechanism including, in combination with a piston and a cylinder in which it operates having provision for the restricted flow of fluid from one to the other end thereof, a timing chamber, signal initiating mechanism, means operable by said initiating mechanism for establishing fluid communication between said cylinder and said chamber and governed by said piston as to the duration of such communication, and means governed by the fluid conditions of said chamber for rendering said initiating mechanism inoperative for a predetermined period after each termination of fluid communication between said cylinder and said chamber.
- 25 40 45 32. Signal device operating mechanism including, in combination with a piston and a cylinder in which it operates having provision for the restricted flow of fluid from one to the other end thereof, a timing chamber, signal initiating mechanism, means operable by said initiating mechanism for establishing fluid communication between said cylinder and said chamber and governed by said piston as to the duration of such communication, and means governed by the fluid conditions of said chamber for rendering said initiating mechanism inoperative during, and for a predetermined period after each termination of, fluid communication between said cylinder and said chamber.
- 50 55 60 65 70 75 80 85 33. Signal device operating mechanism including, in combination with a piston and a cylinder in which it operates having provision for the restricted flow of fluid from one to the other end thereof, a timing chamber, initiating mechanism, and means operable by said initiating mechanism to establish communication between said cylinder and said chamber and thereafter operable by fluid pressure to successively act, after respective time intervals each measured by changes in fluid conditions in said chamber and in said cylinder, to close communication between said chamber and the atmosphere, to restore to and hold said initiating mechanism in normal position, to terminate communication between said cylinder and said chamber, to establish communication between said chamber and the atmosphere, and to cease holding said initiating mechanism in its normal position.

In testimony whereof, I have signed my name to this specification, in the presence of two subscribing witnesses.

HARRY S. SMITH.
